SPINNING DEVICE

Orren M. Gahagan, Dallas, Tex.

Application March 4, 1946, Serial No. 651,941

9 Claims. (Cl. 254—173)

1

This invention relates to a spinning device for operating the spinning cable employed in screwing up sections of drill pipe and similar operations encountered in rotary drilling of earth formations, the principal objects of the invention being to provide a device of this character adapted for control through a pressure fluid; to provide a pressure fluid actuated clutch element for connecting the driving and driven members of the device; to provide manual means for applying and releasing pressure on the fluid for operating the actuator of the clutch element; and to provide auxiliary means for effecting automatic disengagement of the clutch element responsive to wind up of the spinning line or cable.

Other objects of the invention are to provide a spinning device that is of simple, compact construction and of relatively small overall dimension.

In accomplishing these and other objects of the invention hereinafter pointed out, I have provided improved structure, the preferred form of which is illustrated in the accompanying drawings wherein:

Fig. 1 is a perspective view of a cathead equipped with a spinning mechanism embodying the features of the present invention.

Fig. 2 is a longitudinal central section through the cathead.

Fig. 3 is a fragmentary section on the line 3—3 of Fig. 4, particularly illustrating the mechanism for automatically controlling disengagement of the clutch element between the driving and driven members of the device.

Fig. 4 is a cross section on the line 4—4 of Fig. 2, particularly illustrating the clutch element and operating cylinder therefor.

Fig. 5 is a perspective view of the stator and driven member or spinning drum, the parts being shown in disassembled spaced relation together with the hose guide reel and the sections forming the ring to retain the parts in assembly.

Referring more in detail to the drawings:

1 designates a cathead adapted for application to the line shaft 2 of a draw works in a drilling rig and which incorporates the features of the present invention. The cathead includes a rotor or driving member 3, a housing-like stator 4, a catline spool 5 formed as a part of the rotor, a driven member or spinning drum 6 and a hose guide reel 7. The rotor or driving member 3 includes a hub 8 having an axial bore 9 to pass the line shaft 2 when the rotor is mounted thereon and connected in driving relation therewith by a key 10 en-

2

gaged in registering grooves 11 and 12 in the hub and shaft respectively.

Extending circumferentially of the hub at the outer end thereof is an annular web 13 carrying the catline spool 5 which extends therefrom coaxially of the shaft 2. Extending from the opposite side of the web is a driving flange 14 that preferably comprises a sleeve-like cylinder sleeved over the periphery of the web and secured thereto by fastening devices 15. The driving flange 14 has an inner annular face 16 that is adapted to be engaged by a clutch element 17 carried upon the winding drum 6 that is mounted on roller bearings 18 carried on a reduced extension 19 of the hub 8 at one side of an annular retaining shoulder 20 (Fig. 2). Loosely mounted on the extension 19 alongside the spinning drum is the hose guide reel 7 that is secured in position by a ring 21 including mating sections 22 and 23 having internally extending ribs 24 engaged within an annular groove 25 of the hub as best shown in Figs. 2 and 5. The sections of the ring are secured together by fastening devices such as bolts 26 that extend through ears 27 at the ends of the respective sections.

The spinning drum constitutes the driven member and comprises a hub 28 carrying the bearings 18 and having an annular web 29 at the end adjacent the hose guide reel 7. The annular web carries a laterally extending circumferential flange 30 that extends over the driving flange as shown in Fig. 2. The flange 30 has annular side flanges 31 and 32 on the outer edges thereto to form winding space 33 for a spinning line or cable 34 that is wound thereon when the winding drum is connected in driven relation with the driving member by means of the clutch 17.

The clutch member 17 includes a resilient arcuate band 35 having spaced apart ends 36 and 37 interconnected by a fluid pressure actuator 38 and which cooperates with a slotted ear 39 to support the clutch band concentric with the driving flange 14. The ear 39 is diametrically arranged with respect to the actuator and projects inwardly from the band to receive in the slot 40 a pin 41 that extends laterally from the inner face of the web of the spinning drum as shown in Fig. 4. The band preferably carries on the exterior side thereof a lining 42 for enhancing driving contact with the driving flange.

The fluid pressure actuator includes a cylinder 43 having pistons 44 and 45 reciprocably mounted therein for movement to and from a lateral port 46 of a tubular neck 47 extending through an opening 48 in the web 29 of the spinning

drum. The pistons are connected with the ends of the bands by rods 49 slideable through openings 50 in heads 51 of the cylinder and which are pivotally connected as at 52 with ears 53 on the inner face of the band. The clutch band is normally retained in contracted position with the lining out of contact with the driving flange by a spring 54 having the ends thereof secured to the ears 53.

The hose guide reel as best shown in Fig. 5 includes an annular web 55 provided on the sides thereof with side flanges 56 and 57 for retaining a hose 58 therebetween during rotation of the spinning drum.

The stator or housing 4 includes a circular web 60 loosely encircling the flange 56 of the guide reel and which carries a laterally projecting annular flange 61 that extends over the spinning drum and forms a housing therefor as best shown in Fig. 2. The housing is supported in substantially coaxial relation with the shaft by an arm 62 that extends from the web and is adapted for anchorage to a part of the draw works (not shown) for example, the jackpost supporting the bearing for the shaft 2.

The circumferential flange of the stator housing has a notch-like opening 63 in registry with the spinning drum through which the spinning line or cable 34 extends for wrapping the end thereof around a drill pipe section as later described. The other end of the spinning cable is anchored to the spinning drum by extending the end through an opening 64 of the flange 31 and tying a knot 65 therein. To facilitate tying of the knot, the circular web of the housing may be provided with an opening 66 through which the end of the spinning line may be projected to permit tying of the knot, after which the line is redrawn through the opening to bring the knot into contact with the side of the flange. The housing also has an opening 67 for passing the hose 58.

In order to supply a fluid pressure to effect expansion of the clutch band, the hose 58 leads from the actuator 38 to the source of fluid pressure which provides a pump 68 having a fitting 69 provided with a branch 70 connected with the hose 58. The fitting also includes a branch 71 connected by a duct 72 with a fluid supply vessel 73, a check valve 74 being inserted in the duct so as to maintain pump pressure when fluid is being supplied through the hose 55 to actuate the clutch band.

In order to prevent overwinding of the spinning cable on the spinning drum, I provide an auxiliary means for automatically releasing pressure from the actuator to the storage vessel 73 when a predetermined number of wraps of spinning line have been made on the winding drum. This is accomplished by means of a lever 75 pivotally mounted as at 76 between ears 77 which project from the flange of the stator housing in registry with a slot 78 aligning with the winding space of the spinning drum as best shown in Fig. 3. The lever is formed so that a portion thereof extends into the space to contact the cable wound therein. This is effected by forming the lever with an arm portion 79 extending through the slot and carrying a bar portion 80 having an arm 81 extending outwardly through the slot so that the bar portion of the lever is retained in bridging relation with the winding space on the drum and adapted to be moved outwardly in case a second layer of spinning cable should tend to wind thereon to effect rocking of 75

the lever and actuation of a valve 82 mounted in fixed position on the circular web of the housing and which has an actuating arm 83 connected by a link 84 with the arm of the lever

5 75. The valve has an inlet 85 connected by a duct 86 with a branch 87 of the fitting 69. The valve also has an outlet 88 connected by a duct 89 with the vessel 73. Therefore, if more than a predetermined number of layers are wound on the reel, the valve 82 opens connection between the ducts 86 and 89 to bypass the pressure fluid to the vessel so that the pressure drops in the cylinder 38 and the spring 54 is effective in contracting the clutch band and release the driving connection with the driving flange.

10 15 In using the apparatus constructed and assembled as described, the clutch band 37 is mounted on the web 29 of the spinning drum and the spinning drum 6 is mounted on the hub 19 of the rotor or driving member 3. The hose guide reel 7 is then sleeved over the hub 19 and the parts are retained in assembly by application of the retaining ring 21 which includes the sections 22 and 23. The stator housing 4 is then sleeved over the shaft 2 and secured concentrically therewith by attaching the bracket arm 62 with a fixed part of the draw works.

15 20 25 30 35 40 45 The assembly is then mounted on the shaft 2 so that the groove 11 in the hub passes over the key 10. The fluid pressure connections 58, 72 and 69 are then made with the fluid pressure actuator 38 and valve 82, pump 68 and vessel 73, the pump 68 being located in convenient reach of the operator, however, the storage vessel 73 may be mounted in any convenient position in the drilling rig, but it is desirable that the vessel be located relative to the valve 82 so as to promote flow through the duct 89. The spinning drum is then turned so that the opening 64 therein registers with the opening 66. An end of the spinning line 34 is projected through the opening 63 of the stator housing and threaded through the opening 64 so that the end projects through the opening 66. A knot 65 is then tied in the line and the line is retracted through the opening 66 so that the knot 65 engages the side of the spinning drum (see Fig. 1).

50 55 60 65 70 When pressure in the clutch actuating cylinder 38 is released through raising of the pump handle 90 by the spring 91, the pressure drops so that the band contracting spring 54 is effective in holding the clutch band 35 out of contact with the driving flange 14. Therefore, the shaft 2 and driving member 3 may rotate during use of the spinning drum 6. When it is desired to use the spinning line 34, the free end thereof is coiled about a section of drill pipe (not shown) to be threaded into the pipe supported in the bore hole in such a direction that pull of the cable will impart a turning movement of the drill pipe section so as to turn it onto the threads of the section suspended in the bore hole. After coiling or wrapping of the spinning line 34, the lever 90 of the pump 68 is pushed downwardly against action of the spring 91 so that pressure is established through the hose 58 in the pressure cylinder 38 to effect outward movement of the pistons 44 and 45 and expansion of the clutch band 17 into contact with the driving flange 14 of the rotor. The clutch band 17 being carried by the spinning drum effects rotation thereof to wind the spinning cable 34 about the periphery of the spinning drum as shown in Fig. 3 to produce the turning move-

ment of the drill pipe section when the spinning cable unwinds therefrom.

Should the operator of the device retain the driving engagement so that too much of the cable 34 is likely to be wound on the spinning drum, the excess layers will effect rocking of the lever 75 so as to open the valve 82 and establish connection between the pressure line 86 and the vessel 73, thereby relieving pressure between the pistons 44 and 45 so that the spring 54 is effective in contracting the clutch band and returning the pistons to their original position.

From the foregoing it is obvious that I have provided a cathead with a spinning mechanism adapted to be operated by a pressure fluid and which is provided with a safety mechanism for automatically suspending a spinning operation when a predetermined number of coils has been formed about the spinning drum.

It is also obvious that I have provided a simple and compact mechanism that is positive and safe in operation.

What I claim and desire to secure by Letters Patent is:

1. An apparatus of the character described including a driving member, a driven member, clutch means for connecting and disconnecting said members in driving relation, a pressure fluid operated actuator for the clutch means, a storage vessel for retaining fluid medium under a low pressure, duct means connecting the vessel with the actuator, means in said duct for applying pressure to the fluid medium to actuate the clutch means, a check valve in said duct means intermediate the pressure applying means and the storage vessel, and auxiliary means for releasing said pressure to that contained in the storage vessel.

2. In an apparatus of the character described, a driving member, a driven member for winding a spinning cable, a spinning cable connected with the driven member to wind on the driven member, clutch means for connecting and disconnecting said members, actuating means for effecting said connection and disconnection of said members by the clutch means, an auxiliary means contacting the spinning cable for automatically disconnecting the clutch means.

3. In an apparatus of the character described, a driving member, a driven member for winding a spinning cable, a spinning cable connected with the driven member to wind on the driven member, clutch means for connecting and disconnecting said members, a pressure fluid operated actuator for the clutch means, means for supplying fluid medium to said actuator under pressure for effecting actuation of said clutch means and for releasing pressure on the fluid medium to release the clutch means, and an auxiliary clutch releasing means contacting the spinning cable for automatically releasing pressure in said actuator.

4. An apparatus of the character described including, a spinning drum member, a driving member, means supporting said members in coaxial alignment, a clutch flange on one of said members, a clutch element carried on the other of said members and engageable with said clutch flange to effect a driving connection between said members, a hydraulic cylinder carried by one of the rotatable members for actuating said clutch element, a hose connected with the hydraulic cylinder, means connected with said hose for supplying pressure medium to the hydraulic cylinder to actuate the clutch element, a guide reel for guiding the hose during rotation of the spin-

ning drum, and means responsive to winding of a spinning line on the spinning drum for releasing the pressure fluid from the hydraulic cylinder.

5. An apparatus of the character described including, a spinning drum member, a driving member, means supporting said members in coaxial alignment, a clutch flange on one of said members, a clutch element carried on the other of said members and engageable with said clutch flange to effect a driving connection between said members, a hydraulic cylinder for actuating said clutch element, a guide reel carried on said supporting means in coaxial alignment with the spinning drum member, a hose connected with the hydraulic cylinder and arranged to wrap on the guide reel, means connected with said hose for supplying pressure medium to the hydraulic cylinder to actuate the clutch element, and means responsive to winding of a spinning line on the spinning drum for releasing the pressure fluid from the hydraulic cylinder.

6. An apparatus of the character described including a spinning drum member, a cable for winding on the spinning drum member, a driving member, means supporting said members in coaxial alignment, a clutch flange on one of said members, a clutch element carried on the other of said members and engageable with said clutch flange to effect a driving connection between said members, a hydraulic cylinder for actuating said clutch element, a flexible duct connected with the hydraulic cylinder, means connected with said duct for supplying pressure medium to the hydraulic cylinder to actuate the clutch element and to release pressure on said medium, a pressure relief valve, means supported in position relative to the spinning drum member for contacting the cable wound on said member, and an operative connection between the contacting means and said valve for actuating the valve.

7. An apparatus of the character described including, a spinning drum member, a cable for winding on the spinning drum member, a driving member, means supporting said members in coaxial alignment, a clutch flange on one of said members, a clutch element carried on the other of said members and engageable with said clutch flange to effect a driving connection between said members, a hydraulic cylinder for actuating said clutch element, a guide reel carried on said supporting means in coaxial alignment with the spinning drum member, a flexible duct connected with the hydraulic cylinder, means connected with said duct for supplying pressure medium to the hydraulic cylinder to actuate the clutch element and to release pressure on said medium, a stator enclosing the spinning drum, a pressure relief valve carried on the stator and having connection with said pressure supplying means to provide an auxiliary release for said pressure, cable contacting means movably supported on the stator in position to be actuated by the cable when winding on said drum, and an operating connection between the contacting means and said valve for actuating the valve responsive to movement of the contacting means.

8. An apparatus of the character described including, a spinning drum member, a driving drum member, means supporting said members in coaxial alignment, a clutch engaging means on one of said members, a clutch element carried on the other of said members and engageable with said clutch engaging means to effect a driving connection between said members, a hydraulic cylinder carried by one of the members for actu-

ating said clutch element, a duct having a flexible portion connected with the hydraulic cylinder, means connected with said duct for supplying pressure fluid to the hydraulic cylinder to actuate the clutch element and to release pressure on said supplied fluid, a pressure relief valve connected with said duct, means responsive to winding of a spinning line on the spinning drum to actuate said relief valve, a vessel for retaining said fluid, a duct connecting the relief valve with said vessel for discharging pressure to the vessel that is relieved through said valve, a duct connecting the storage vessel with the pressure supply means, and a check valve in the duct intermediate the vessel and the connection of the first named duct with said pressure supply and release means.

9. In an apparatus of the character described, a rotor having a hub portion adapted to be mounted on a driving shaft, said driving member having an annular flange extending coaxially about the hub in spaced relation therewith, a driven member having a hub portion rotatably mounted on the hub of the driving member and extending into said space, said driven member having a radial annular flange and a lateral cable winding portion extending circumferentially of the annular flange on the driving member for winding a cable, friction clutch means carried by

5 said radial flange of the driven member and adapted to frictionally engage the annular flange on the driving member, a pressure cylinder carried by said radial flange of the driven member and having an operative connection with the friction clutch to move said friction clutch into driving engagement with said annular flange, a guide reel rotatably mounted on the hub of the driving member, a flexible duct connected with the cylinder and adapted to wrap around the guide reel and unwind therefrom upon turning of the driven member, and a housing enclosing the driven member and the guide reel, said housing having openings for passing the cable and said flexible duct.
